ELECTRON TUBES, IN A RETARDING FIELD CIRCUIT ARRANGEMENT

Rudolf Urtel, Berlin, Germany, assignor to Telefunken Gesellschaft für Drahtlose Telegraphie m. b. H., Berlin, Germany, a corporation of Germany

Application January 6, 1933, Serial No. 650,495
In Germany March 24, 1932

5 Claims. (Cl. 250—27)

With a thermionic tube connected in a retarding field circuit arrangement, if full utilization of the properties of such circuit is to be obtained, it is necessary that the cathode of the tube show 5 a definite saturation point for emission current. In actual tubes the saturation point is, however, more or less indefinite and is not reached when normal voltages are applied to the tube elements. Application Serial No. 654,091 filed Jan. 28, 1933 10 discloses ways and means of overcoming the disadvantages of this actual lack of definiteness of saturation and the present invention discloses other circuit arrangements for attaining the same end.

15 According to the invention instead of an auxiliary-grid arrangement as suggested in the patent application Serial No. 654,091, being provided inside the tube to be used in the circuit scheme, a resistance R is included in the joint circuit grid and plate circuits which, regardless of the applied potential, supplies a constant current as 20 illustrated in Fig. 1. In this figure the battery 16 has its positive terminal connected to the control grid and its negative terminal to the cathode 25 through a resistor R, the grid current I_g may then be read on an ammeter connected as shown. A second battery E_k has its positive terminal connected to the plate or anode and its negative terminal to the end of resistor R as shown, the 30 plate current I_a may then be read on a second ammeter connected as shown. The fall of voltage across the said resistance conditions the presence of a compensating voltage,

$$E_k = (I_a + I_g) \times R + E_a$$

35 in order that the retarding electrode may again be at a potential differing but slightly from the filament. In this formula I_a is the value of the plate current, I_g the value of the grid current, 40 R the value of the resistor common to the grid and plate circuits and E_a is the voltage between anode and cathode in the absence of R. If the cathode current through R were to increase, the grid becomes less positive with respect to the 45 cathode, thereby decreasing the grid current directly as fewer electrons are attracted to it and the plate current is also decreased by the mutual conductance of the grid to plate of the tube. By selecting R of the proper value the 50 total current between the cathode and the cold elements of the tube may thus be maintained substantially constant, irrespective of voltage variations. The resistance would be represented, for instance, by a screen-grid tube. Hence, according 55 ing to this invention, and as illustrated in Fig. 2

(seeing that solely the resistance characteristics of this tube are to be utilized), a screen-grid tube 1 provided, for instance, in the radio frequency amplifier stage of a receiver arrangement is employed to act as a resistance R in the joint 5 circuit I_g + I_a of the tube 2 used in the retarding-field scheme. Also by this means conditions are obtained so that cathodes presenting a definite saturation in the retarding-field tube will be dispensable. As shown in Fig. 2 the tunable 10 input circuit of screen grid tube 1 comprises a coil 3 shunted by a variable condenser 4, the screen 5 being given a positive potential by a battery 16 and the plate 12 of tube 2 a positive potential by a battery 17. In the plate circuit 15 of amplifier 1 is a parallel resonant circuit comprising coil 10 and variable condenser 11, the high potential end of coil 10 being connected to plate 6 through a condenser 9. A conductance path including coil 8 and lead 14 connects the cathode of tube 2 with the plate 6, the direct plate current I_a of tube 2 passing over this path to the plate 6 as does also the grid current I_g of tube 2. The grid current of tube 2 is supplied by a battery 18 through a resistor 15. From the 20 described arrangement it is apparent that the plate-cathode resistance of the screen grid tube 1 takes the place of resistor R of Fig. 1 and that the total current through tube 2 and battery 17 up to the point 19 remains substantially constant 25 irrespective of variations in the radio frequency current through the plate of tube 1. In other words the high impedance of screen grid tube 1 may replace resistor R of Fig. 1 without interfering with the function of tube 1 as a radio frequency amplifier. At point 19 the total current I_a + I_g divides, the portion I_g flowing through resistor 15 to the grid of tube 2 while the portion I_a passes to the plate 12 through coil 10. Any desired means (not shown) may be used for 30 impressing the radio frequency currents to be amplified on the control grid circuit 3, 4 of tube 1 and any desired means (not shown) used for transferring the amplified currents from its plate circuit including coil 10. Condensers 7 and 13 35 are the usual by-pass condensers. Due to the high plate impedance of the screen grid tube for alternating current, the arrangement provides a large control of the voltage of the grid of tube 2 and at the same time the battery 17 need not 40 be as large as would be necessary if an equal resistance value in the form of a single resistor 45 such as R of Fig. 1 were used.

What is claimed is:

1. An arrangement for the production of a sub- 50

55

- stantially constant current, comprising the combination of a vacuum tube having a control grid, cathode and anode, an output circuit connecting said cathode and anode and including a source 5 of potential connected to maintain said anode constantly at a positive potential with reference to said cathode, an input circuit connecting said cathode and control grid, a source of potential for maintaining said grid at a positive potential 10 with reference to said cathode and an element having a high resistance connected in both said input and output circuits the resistance of said element being designed to maintain the total current therethrough substantially constant irrespective of whether the cathode current of said tube is saturated.
2. In a device of the class described, the combination of a vacuum tube having a control grid, cathode and anode, an output circuit connecting 15 said cathode and anode and including a source of potential connected to maintain said anode constantly at a positive potential with reference to said cathode, a grid circuit connecting said cathode and control grid and including a source 20 of potential connected to maintain said grid at a positive potential with reference to said cathode, and a second vacuum tube having its plate conductively connected to the cathode of said first named tube and its cathode conductively connected to the anode of said tube whereby the 25 direct plate current of said first named tube passes between the plate and cathode of said second tube.
3. The combination defined in the preceding 30 claim in which said second named tube has a screen grid and a positive source of potential connected to said screen grid.
4. In a device of the class described, the com-

bination of a vacuum tube having a control grid, cathode and anode, an output circuit connecting 5 said cathode and anode and including a coil and variable condenser connected in parallel, a grid circuit connecting said cathode and control grid and a second vacuum tube having its plate conductively connected to the cathode of said first named tube and a circuit connecting its cathode to the anode of said tube, said circuit including the series connection of a source of 10 positive potential and said coil, said second tube having a control grid and a screen grid, means for applying a positive potential to said screen grid, a tunable input circuit connecting 15 said control grid and cathode, the grid circuit of said first named tube comprising a source of potential having its negative terminal conductively connected to said screen grid and also being arranged to provide a conductive connection to the cathode of said screen grid tube.

5. In a device of the class described, the combination of a vacuum tube having a control grid, cathode and anode, a coil, a conductive connection between one end of said coil and said anode, a source of potential having its negative terminal 20 conductively connected to the other end of said coil and its positive terminal to said grid, a second vacuum tube having a cathode, a control grid and a plate, a conductive connection between said plate and the cathode of said first tube, 25 means coupling said plate to the first named end of said coil, an input circuit connecting the grid and cathode of said second tube and a source of potential having its negative terminal connected to the cathode of said second named tube and its positive terminal to the negative terminal of 30 said first named potential source.
